UNITED STATES PATENT OFFICE.

JOSEPH A. KRANTZ, OF CANAL DOVER, OHIO, ASSIGNOR TO THE REEVES MANUFACTURING COMPANY, OF CANAL DOVER, OHIO, A CORPORATION OF OHIO.

PLANT FORCER AND PROTECTOR.

1,266,131.

Specification of Letters Patent. Patented May 14, 1918.

Application filed July 6, 1915. Serial No. 38,137.

To all whom it may concern:

Be it known that I, JOSEPH A. KRANTZ, a citizen of the United States, residing at Canal Dover, in the county of Tuscarawas 5 and State of Ohio, have invented a new and useful Plant Forcer and Protector, of which the following is a specification.

My invention relates to plant forcers and protectors made up of detachable members. 10 The objects of my present invention are, first, to provide a device of the character described which can be knocked down for shipment or storage, second, to provide means for easily connecting the various 15 members to produce the structure for actual use, and third, for the growth and the protection of plants.

These objects, together with other objects readily apparent to those skilled in the art, 20 may be attained by the construction illustrated in the accompanying drawings, although the invention may be embodied in other forms, the construction illustrated being chosen by way of example.

25 In the accompanying drawing:

Figure 1 is a perspective view showing the different parts properly assembled.

Fig. 2 is a vertical section.

Fig. 3 is a sectional view of one of the 30 joint or connecting flanges.

Fig. 4 is a section on line 4—4, Fig. 2.

Fig. 5 is a view showing the connecting flanges detached from each other.

Fig. 6 is a view showing a portion of one 35 side, the back showing parts broken away and illustrating a portion of the top.

Similar numerals of reference indicate corresponding parts in all the figures of the drawing.

40 In the accompanying drawing, 1 represents the side members which are quadrangular in shape and are so formed for the purpose of producing a structure when the various parts are assembled which will be of

45 such shape that it can be placed in position to receive proper light and heat. The side members 1 are provided at their opposite ends with the folded flanges 2, which are for the purpose of receiving the open folded flanges 3 formed upon the back 4 and the front or narrow plate 5. The folded flanges

2 and 3 are so formed that they can be slidably connected together and when slidably connected together are in the position shown in Fig. 3. The top inclined edges of the 55 side members 1 are provided with the open grooves 6, which are for the purpose of receiving and holding the glass top or cover 7. The plate 5 is arranged as shown in Fig. 1 and Fig. 2 and is connected by means of 60 the seam flanges 2 and 3. The plate 5 when properly connected to the side members 1 will constitute a support or stop for the glass top 7, the lower edge or portion of said glass top coming in contact with the 65 plate, this feature being best illustrated in Fig. 2.

For the purpose of providing ventilation, the glass top 4 should be formed somewhat shorter than the length between the plate 70 5 and the back plate 4, by which an air space 8 is provided.

For the purpose of strengthening and stiffening the various metal parts, the front plate or member 5 is provided with the 75 lateral flanges 9, the side member 1 with the lateral flanges 10, and the back member with the top and bottom flanges 11. It will be understood that by forming the joints of open hooked flanges, said flanges can be telescopically connected or the parts slid into position to connect all of the metal parts, by which arrangement the parts constituting the structure can be shipped or stored in a knock-down condition and when desired for 80 use can be easily and quickly connected together to produce the structure such as shown in Fig. 1. It will be understood that by forming the strengthening flange 11 at the top of the back plate it serves a double 85 purpose, to-wit, said flange will act as a guide to enter the glass tops into the open grooves formed upon the top edges of the inclined side members.

Having fully described my invention what 90 I claim as new and desire to secure by Letters Patent, is:

In a knock down plant forcer and protector, the combination of side members having inclined top edges, said side members 100 provided with open hooked flanges, the bottom edges of said members provided with

strengthening flanges, the inclined top edges of said side members provided with open grooves, back and front plates slidably connected to the hooked flanges of the side members, said back and front plates provided with strengthening flanges, a transparent cover slidably mounted in the open

grooves formed in the inclined top edges of the said members, all arranged, substantially as specified. ¹⁰

In testimony that I claim the above, I have hereunto subscribed my name.

JOSEPH A. KRANTZ.
